UNITED STATES PATENT OFFICE.

CHRISTIAN A. SCHMIDT, OF NEW YORK, N. Y.

DESIGN FOR FRINGE.

SPECIFICATION forming part of Design No. 13,854, dated April 10, 1883.

Application filed March 10, 1883. Term of patent 14 years.

To all whom it may concern:

Be it known that I, CHRISTIAN AUGUSTUS SCHMIDT, a citizen of Russia, residing in the city, county, and State of New York, have invented and produced a new and original Design for Fringes, of which the following is a specification.

Reference is to be had to the accompanying drawing, forming a part of this specification, 10 and which is a front elevation of a piece of a fringe illustrating my design.

The leading feature of my design consists of a series of pendants rounded at one end, concaved to form necks near their other ends, 15 and attached to a suitable heading.

A are pendants, which are rounded at one end, and are concaved or contracted near their other ends to form necks. The pendants A are suspended by strands B from any suitable 20 heading, C. To the strands B, at the lower

ends of the pendants A, are attached tufts or balls D, and similar tufts or balls can, if desired, be attached to the said strands at the upper ends of the said pendants.

I claim—

1. The design for a fringe herein shown and described, the same consisting of the series of pendants A, rounded at one end, concaved to form necks near their other ends, and suspended from a suitable heading. 25

2. The design for a fringe herein shown and described, the same consisting of the series of pendants A, rounded at one end, concaved to form necks near their other ends, suspended from a suitable heading, and provided with 30 tufts or balls D at their lower ends. 35

CHRISTIAN A. SCHMIDT.
